United States Patent Office

Des. 223,616
Patented May 16, 1972

223,616

FILE RACK

David Woods, Quakertown, Pa., assignor to J. G.
Furniture Company, Inc., New York, N.Y.

Original design application Jan. 2, 1969, Ser. No. 15,184.
Divided and this application May 19, 1969, Ser. No.
17,201

Term of patent 14 years

Int. Cl. D6—99

U.S. Cl. D33—3

FIG. 1.

FIG. 3.

FIG. 2.

FIG. 5.

FIG. 4.

FIG. 1 is a perspective view of a file rack embodying my new design;

FIG. 2 is a top plan view of the file rack of FIG. 1;
FIG. 3 is a bottom plan view of the file rack of FIG. 1;
FIG. 4 is a side view of the file rack of FIG. 1; and
FIG. 5 is an end view of the file rack of FIG. 1.

This application is a division of my application Ser. No. D. 15,184, filed Jan. 2, 1969.

I claim:

The ornamental design for a file rack, as shown.
